UNITED STATES PATENT OFFICE.

JAMES L. PERRY, OF SMITHVILLE, NEW JERSEY, ASSIGNOR TO H. B. SMITH MACHINE COMPANY, OF SMITHVILLE, NEW JERSEY, A CORPORATION OF NEW JERSEY.

SANDPAPERING-MACHINE.

No. 891,950.

Specification of Letters Patent.

Patented June 30, 1908.

Application filed September 24, 1906. Serial No. 388,059.

To all whom it may concern:

Be it known that I, JAMES L. PERRY, a citizen of the United States, residing at Smithville, county of Burlington, and State 5 of New Jersey, have invented a new and useful Improvement in Sandpapering-Machines, of which the following is a full, clear, and exact description, reference being had to the accompanying drawings, which form a part 10 of this specification.

My invention embodies improvements on the sand-papering machine set forth in Letters Patent No. 657,357, dated September 4, 1900, and has for its object to provide new 15 and improved means for driving the shaft of the endless carrier from the driving shaft, to improve the construction of the endless carrier, to provide means to lubricate the bearings between the links and lugs of the endless 20 carrier and also the ways over which the upper reach of the carrier travels, to provide new and improved means for independently adjusting the four corners of the table, to provide means for removing dust from the 25 working face of the endless carrier, and to provide new and useful means by which the precise, adjustment of the sanding drums to regulate the depth of the cut may be indicated so that the adjustment may be regulated to a nicety before the work is fed into 30 the machine.

In the drawings: Figures 1 and 2 are side elevations of the machine looking respectively from opposite sides thereof, the mechanism for raising and lowering one corner of the table being shown in Fig. 1. Fig. 1^a is an inverted plan view, partly broken away, of one of the corner adjusting devices. Fig. 3 is a detail side elevation of the mechanism 35 for raising and lowering the drum and the indicator attachment therefor. Fig. 4 is a transverse sectional view of the same. Fig. 5 is a detail longitudinal sectional view of one of the lags, on one of the lugs of the carrier. Fig. 6 is a detail view of one of the links. Fig. 6^a is a detail view of one of the pins and illustrating its mode of engagement with opposite links. Fig. 7 is a detail longitudinal sectional view of the mechanism for 40 lubricating the ways for the carrier. Fig. 8 is a plan view of the same.

10 is the machine frame, 20 the vertically-adjustable carrier supporting table, 30 the endless carrier and 60 the sanding drums.

11 is the main driving shaft rotating in 55 bearings in the machine frame.

12 is a sprocket wheel on the main driving shaft.

15 is a secondary driving shaft turning in 60 bearings on the machine frame.

14 is a sprocket wheel on the secondary driving shaft.

13 is a sprocket chain connecting sprocket 65 wheels 12 and 14.

22 is the shaft for driving the endless carrier, rotating in bearings on the table 20 near one end thereof.

150, 210 are expansion links pivoted respectively to shafts 15 and 21 and providing bearings for an intermediate shaft 18. A 70 pinion 16 on shaft 15 engages a gear 17 on shaft 18, and a pinion 19 on shaft 18 engages a gear 21 on shaft 22.

By the described connections the driving shaft drives the endless carrier shaft at a 75 much reduced speed, and provision is made for a vertical adjustment of the carrier table without affecting the driving connections between the main shaft and the driving shaft for the endless carrier.

The shaft 22 has the two sprocket wheels 23. A shaft 25 turns in bearings near the other end of the table 20 and has the two sprocket wheels 24. The endless carrier 30 extends about the two pairs of sprocket wheels 23 85 and 24.

The endless carrier 30 comprises links 31, lags 32. The lags extend from one side to the other of the carrier, and each two adjacent lags are connected by means of two 90 pairs of links engaging respectively the sprocket wheels 23 and 24 at opposite sides of the table. The lags travel over ways 26 on the table.

The connections between the lags and 95 links of the carrier are as follows: Secured to the underside of each lag are two lugs 33 (see Figs. 5 and 7). Each lug is provided with two transversely extending orifices 36 through which extend pins 369. The pins 369 extend respectively into orifices 39 in the corresponding ends of two pairs of links, one pair of links being similarly connected with the adjacent lug of one of the next adjacent lags, and the other pair of links being similarly 100 connected with the adjacent lug of the other next adjacent lag. The orifices in the lugs of the lags are circular to permit the pins to

turn freely therein. The pins however, are held tight in the orifices of the links, to avoid wear. This is effected, in the particular construction shown, by making the orifices in the links of non-circular shape to prevent the pins turning therein, the inserted end of the pins having, of course, a corresponding sectional contour. It will be understood, however, that only the orifices at one end of a link need be non-circular, provided the orifice at the other end of its companion link is non-circular, and such a link is shown in Fig. 6.

The bearings between the pins and the lugs of the lags may be lubricated by the means shown in Fig. 5, comprising a longitudinally extending recess 37 in the lug intersecting the edges of the holes for the pins. The recess 37 may contain any suitable lubricating material.

To lubricate the ways for the lags, the following means are provided (see Figs. 7 and 8.) Connecting the side-walls of the table, and beneath the ways, is the box 40. Supported from bolts 41, depending from brackets 42 on the table, is a trough 43 extending substantially from end to end of the box and adapted to contain oil. Projecting upwardly from the trough are standards 44 in which turns shaft 45 projecting beyond the ends of the table and having squared ends adapted to receive a handle 460. Secured to the shaft 45 are brushes 46 extending into orifices 47 in the ways 26. By turning the shaft 45 while the sander is in operation, the brushes 46 apply oil to the inner faces of the lags, which distribute the oil along the working faces of the ways.

The lags of the carrier are provided on their outer surfaces, as usual, with rubber cushions 38, which, in the operation of the sander, tend to clog with dust. To clean the dust from the rubber cushions, the following arrangement is provided (see Fig. 1). Secured to the shaft 15 is a gear 51 engaging a gear 52 on the shaft 53. Secured to the shaft 53 is a gear 54 engaging a gear 55 on the shaft 56. Secured to shaft 56 is the brush 57. As the carriers travel, the brush 56 turns and cleans thoroughly the rubber cushions and the spaces between the cushions. The shaft 56 turns in bearings on the table and the shaft 53 is journaled in links 151, 530 attached respectively to shafts 15 and 53.

The following means are provided for vertically moving the tables so as to provide for operating upon different thicknesses of material (see Figs. 1 and 2.) 80 are four upright screw threaded shafts at the four corners of the table. Each shaft has on its lower end the bevel gear 81. Each threaded shaft engages, near its upper end, a nut 82 which telescopes within a box 83 through which the upper end of shaft 80 loosely extends.

Confined between the nut and box is a spring 84. The box 84 has a flange 85 which is bolted to the table. By turning the shafts 80 in one direction, the nuts 82 are raised against their corresponding springs 84, which, acting upon their corresponding boxes 83, elevate the table. By turning the shafts 80 in the opposite direction the nuts 82 are lowered and the table sinks to the extent permitted by the springs 84. Appropriate means are provided to enable the shafts 80 to be operated in unison, either by hand, or from the main driving shaft, with which they are connected by suitable clutch mechanism. The mechanism for operating the shafts 80 in unison need not, however, be described, as such mechanism is old and well known and is fully set forth in my first patent hereinbefore referred to.

To provide for leveling the table, that is, adjusting each of the four corners independently, the following construction is provided. On the nut 82 is the annular flange 86 having orifices 860 through which extend loosely bolts 87 engaging screw threaded holes 880 in an annular flange 88 on the box 83. By screwing down the bolts 87, the spring 84 raises box 83 and the corresponding corner of the table. By screwing up the bolts 87, the corresponding corner of the table drops to the extent permitted by the spring.

To secure a finer adjustment, the threaded holes in the box and the holes in the nut are of a different number, the arrangement being such that the number of one series of holes (say the threaded holes) is a multiple of the other series of holes. The screws may be withdrawn, the nut turned on the threaded shaft to bring the holes therein into alignment with another series of holes in the box, and the screws then re-inserted.

The following means are provided to support the sanding drums 60 and enable them to be raised and lowered to regulate the depth of the cut. (See Figs. 3 and 4). 61 are pins on opposite sides of the machine frame, there being a pair for each drum. On these pins are pivoted the arms 62. Between the ends of the arms are bearings 63 for the drum shaft 65. The outer end of one of these arms forms the journal for one end of a shaft 66, while the outer end of the other arm carries a box 67 in which the other end of shaft 66 is journaled, the shaft projecting into the box. The shaft has, near each end, an eccentric 68 which engages a block 69 slidably laterally on the frame of the machine. On the end of the shaft 66 which projects into the box 67 is a worm-wheel 76, and extending into the box, and engaging the worm wheel is a worm 77. To raise or lower the drum, the worm 77 is turned by means of the handle 70, which turns the shaft 66. By reason of the eccentric bearing of the shaft 66 in the block 69, and the capacity of the block to move lat-

erally but not vertically, the shaft 66 is either raised or lowered, thereby lifting the arms 62 and the drum 60 and thus regulating the depth of the cut. To enable the depth 5 of the cut to be accurately determined, a pointer 71 is secured to the shaft 66 and an indicator 72 is placed on the outside of the box 67.

I have not herein claimed the means for 10 lubricating the ways and the inner face of the carrier, nor have I claimed the means whereby the lags of the carrier are connected together, as these form the subject matter of separate divisional applications.

15 Having now fully described my invention, what I claim and desire to protect by Letters Patent is:

1. In a sand papering machine, the combination with the main frame, the vertically 20 movable table, the endless carrier and the carrier driving shaft journaled in the table, of a shaft journaled in the main frame, an intermediate shaft, links respectively on the first two shafts and in which the intermediate 25 shaft is journaled, and gears connecting the intermediate shaft with each of the other two shafts.

2. In a sand-papering machine, the combination with the main frame, the vertically 30 movable table and the endless carrier, of the main driving shaft and the secondary driving shaft both journaled in the main frame; driving connections between the two shafts, a driving shaft and an idler shaft both journaled in the table, sprocket wheels on the two last named shafts, the endless carrier extending about said sprocket wheels, and intermediate shaft, links respectively on the secondary shaft and the endless carrier driving 35 shaft, and in which the intermediate shaft is journaled, and gears connecting the intermediate shaft respectively with the secondary driving shaft and the endless carrier driving shaft.

3. In a sand papering machine, the combination with the main frame and the table movable vertically on the frame, of the endless carrier supported on and movable with the table, a shaft journaled in the table and a brush thereon adapted to engage the carrier, 51 a driving shaft journaled in the main frame, an intermediate shaft, links on the driving shaft and brush shaft respectively in which the intermediate shaft is journaled, and driving connections between the intermediate 5 shaft and the other two shafts.

4. In a sand papering machine, the combination with the main frame and the table movable vertically on the frame, of the endless carrier supported on and movable with 60 the table, a shaft journaled in the table and a brush thereon adapted to engage the carrier, a driving shaft journaled in the main frame, and automatically extensible and contractible driving connections between the driving 65 shaft and the brush shaft adapted to maintain the brush in driving relation with its driving shaft notwithstanding adjustments of the table.

5. In a sand-papering machine, the combination with pivoted arms and the sanding drum supported thereon, of a box supported on one of the arms, a shaft journaled in said box, a block laterally slidable on the main frame, an eccentric on said shaft within and 70 engaging the block, means to turn said shaft, a pointer on the shaft, an indicator co-operating with said pointer, and means to turn said shaft.

In testimony of which invention, I have 80 hereunto set my hand, at Philadelphia, on this 14th day of September, 1906.

JAMES L. PERRY.
